UNITED STATES PATENT OFFICE.

ARCHIBALD S. CUBITT, OF SCHENECTADY, NEW YORK, ASSIGNOR TO GENERAL ELECTRIC COMPANY, A CORPORATION OF NEW YORK.

RELAY.

1,025,786.

Specification of Letters Patent.

Patented May 7, 1912.

Application filed September 6, 1907. Serial No. 391,694.

To all whom it may concern:

Be it known that I, ARCHIBALD S. CUBITT, a subject of the King of Great Britain, residing at Schenectady, county of Schenectady, State of New York, have invented certain new and useful Improvements in Relays, of which the following is a specification.

The ordinary form of relay used in connection with the control of dynamo electric machinery comprises a current carrying coil and an iron core arranged for movement therein, said core carrying one or more contact disks which make and break connection between fixed contacts. After such a relay has pulled up the current required to hold it in its raised position is much less than the current required to pull it up. In other words, there is a considerable difference between its raising and its dropping current.

An object of my present invention is to provide a relay which will pull up and drop within a small change of current.

In systems of motor control in which the speed of the motor is regulated by the amount of resistance in the motor circuit, or, if more than one motor is used, by also changing the relation of the motors to one another, these changes being made by a controller, means is often provided for retarding the movement of the controller in case the current in the motor circuit rises higher than a certain value. A convenient form of such retarding means consists in an electro-magnetically operated locking device for the controller, the operation of said locking device being governed by a relay, the actuating coil of which is located in the motor circuit. The ordinary form of relay, which after it has pulled up will not drop until the current through its actuating coil has fallen very considerably, is unsuitable for the motor control system above mentioned, since it will keep the controller locking device in action long after the motor current has fallen below the dangerous value. My improved form of relay is, therefore, particularly adapted for use in connection with control systems of the above described kind since it causes the retardation of the controller only while the current in the motor circuit is truly dangerous.

My invention comprises a relay having means for biasing the core thereof in a di-

rection opposite to that in which the actuating coil tends to move it, and means for automatically increasing the force exerted by said biasing means after the relay has pulled up. With such an arrangement the relay may be made to drop when the current through its actuating coil has decreased to a value only slightly below that at which it pulled up.

My invention will be more clearly understood from the following description of one form in which it may be embodied, taken in connection with the accompanying drawing, in which—

Figure 1 is a front elevation of a relay having my invention embodied therein; Fig. 2 is a side elevation thereof, and Fig. 3 shows diagrammatically a simple motor control system having my improved type of relay applied thereto.

Referring to the drawing, 5 indicates the back or base of insulating material, such as slate, upon which the parts of the relay are mounted. The actuating coil of the relay is shown at 6. An iron core 7 is mounted for movement within the field of the coil 6, being guided in any suitable manner as by means of the rods 8 and 9 which project from its top and bottom and pass freely through brackets 10 and 11 secured to the base 5. The rod 9 carries the usual contact disk 12, mounted in a well known manner between fixed collars 13 and 14, a spring 15 serving to hold the disk 12 yieldingly against the collar 13. This disk, when the core pulls up, bridges fixed contacts 16 and 17 in the usual manner. A collar 18 fixed on the rod 9 may engage with the bracket 11 and serve to limit the downward movement of the core. The parts so far described may be of any suitable and well known construction.

The movable core is biased for movement downwardly, that is, in a direction opposite to that in which the actuating coil when energized tends to move it, by a spring 20 surrounding the rod 9 and placed under tension between the collar 21 adjustably secured to the rod 9, as by a nut 22, and the divided arm 23 of a bell-crank lever pivotally mounted in the bracket 24 secured to the base 5. Lugs 25 integral with the bracket 24 may serve to limit the rotation of the bell-crank lever under the force exerted by

the spring 20. Mounted on the base 5 in co-operating relation to the arm 26 of the bell-crank lever is an auxiliary coil 27. This coil 27 is so arranged that when energized 5 it will attract the arm 26 of the bell-crank lever and cause the same to rock on its pivot, and its other arm 23 to compress the spring 20, thereby increasing the force tending to make the core of the relay drop. The coil 10 27 may be provided with an iron core 28 secured to or made integral with the bracket 24 in order that the torque exerted on this coil may be considerable. The form of this coil is best shown in Fig. 2. The auxiliary 15 coil 27 is connected in series with the actuating coil 6 by the heavy conductor 30 and is connected to the terminal 31 by a heavy conductor 32. The other end of the actuating coil 6 may be connected to the 20 terminal 33 in a suitable and well known manner, as shown in Fig. 1. The auxiliary coil 27 and its co-operating parts are so designed that, while the same current as that required to pull up the relay will sufficiently 25 energize this coil to operate the bell-crank lever and increase the tension on the spring 20, these parts will act more slowly than does the actuating coil 6 in pulling up the movable core 7.

30 In operation when the current in the actuating coil 6 has risen to the necessary value, the core is pulled up. The auxiliary coil 27 being in series with the coil 6 receives the same current and attracts the arm 35 26 of the bell-crank lever, this action, however not taking place until after the core has pulled up, owing to the fact that the coil 27 and its co-operating parts are slower acting than the actuating coil 6 and its co-operating 40 core. Movement of the bell-crank lever under the influence of the auxiliary coil 27 will increase the tension on the spring 20 and thus increase the force tending to cause the core 7 to drop. The effect of thus increasing, after the core 7 has risen, the force exerted on it in opposition to the actuating coil 6 will be to cause the core 7 to drop after a smaller decrease in current than it would if the force exerted by the 45 spring 20 were constant. In other words, the difference between the current at which the relay pulls up and that at which it drops is decreased.

50 In Fig. 3 I have shown a simple motor control system of the separately actuated contact type in which the master-switch is provided with a locking device which will restrain it from further movement if at any time the current in the motor circuit exceeds a certain value, the operation of the locking device being controlled by my new and improved form of relay indicated at A. In Fig. 3 M indicates a motor; R¹, R² and R³ are resistance sections adapted to be introduced into the motor circuit and elimi-

nated therefrom in accelerating; C is a motor controller of the separately actuated contact type adapted to connect the motor to a source of supply and regulate the amount of resistance in the motor circuit; 70 K is a master-switch for governing the operation of the motor controller; and K¹ is an electro-magnetic locking device for the master-switch of any well-known form.

My improved relay has its actuating coil 75 6 and its auxiliary coil 27 connected in series in the motor circuit, as shown, and the fixed contacts 16 and 17 of the relay in the circuit through the actuating coil 6 of the master-switch locking device which is 80 thrown into operation when the relay pulls up and the disk 12 bridges the contacts 16 and 17.

A detailed description of the system of control illustrated in Fig. 3 is believed to be 85 unnecessary since with the exception of the relay A, such systems are well known to those skilled in this art. Suffice it to say that the master-switch K will in its first position connect the motor to the line 90 through all the resistance and that the successive points on the master-switch provide for the operation of the contactors which cut out the sections of resistance R¹, R² and R³. If during the movement of the master- 95 switch the current in the motor circuit exceeds a certain value, the relay A will pull up and the controller locking device K will prevent further movement of the master-switch until the current in the motor circuit has fallen sufficiently to allow the relay A to drop.

While I have shown only one particular construction in which my invention may be embodied and but a single use therefor, I 100 wish it understood that I realize that many other means may be provided for increasing, after the relay has pulled up, the force tending to make it drop, and that it may be used in many other connections. It is my intention to cover all such means in the following claims.

What I claim as new and desire to secure by Letters Patent of the United States, is,—

1. A relay comprising an actuating coil, 110 a core movable in the field thereof, means for biasing said core in a direction opposite to that in which the coil when energized tends to move it, an auxiliary coil energized simultaneously with said actuating coil, and 120 means controlled thereby for increasing the bias on said core after the core has moved under the influence of its coil.

2. A relay comprising an actuating coil, a core movable in the field thereof, a spring 125 biasing said core in a direction opposite to that in which the coil when energized tends to move, an auxiliary coil energized simultaneously with said actuating coil, and means operated by said auxiliary coil for 130

increasing the tension on the spring after the core has moved under the influence of said actuating coil.

3. A relay comprising an actuating coil, a core movable in the field thereof, a spring biasing said core in a direction opposite to that in which the coil when energized tends to move it, an auxiliary coil in series with said actuating coil, and means magnetically operated by said auxiliary coil for increasing the tension on the spring after the core has moved under the influence of said actuating coil. 20

4. A relay comprising an actuating coil, a core movable in the field thereof, a spring

biasing said core in a direction opposite to that in which the coil when energized tends to move it, an auxiliary coil in series with said actuating coil, and a lever device magnetically operated by said auxiliary coil for increasing the tension on the spring after the core has moved under the influence of the actuating coil.

In witness whereof, I have hereunto set my hand this 5th day of September, 1907. 25

ARCHIBALD S. CUBITT.
